UNITED STATES PATENT OFFICE.

ARTHUR T. DAWSON AND GEORGE T. BUCKHAM, OF WESTMINSTER, LONDON, AND
ERNEST F. ELLIS, OF PURLEY, ENGLAND.

GUN-MOUNTING.

1,299,140.

Specification of Letters Patent.

Patented Apr. 1, 1919.

Application filed July 7, 1917. Serial No. 179,269.

To all whom it may concern:

Be it known that we, Sir ARTHUR TREVOR DAWSON, knight, GEORGE THOMAS BUCKHAM, and ERNEST FRANK ELLIS, subjects of the King of Great Britain, residing, respectively, at Vickers House, Broadway, Westminster, in the county of London, England; Vickers House, Broadway, Westminster, in the county of London, England, and The Wood, Furze Hill, Purley, in the county of Surrey, England, have invented certain new and useful Improvements in or Relating to Gun-Mountings, of which the following is a specification.

This invention relates to naval gun mountings particularly those of the pedestal type.

According to the invention we provide means interposed between the carriage and the mounting or other part that does not move in training, for preventing the gun from being moved laterally at a greater speed than that obtainable by the actuation of the training mechanism, thereby obviating liability of the gun "taking charge." The said means preferably comprise a dash pot which is operated by the movements of the gun in training and is of such a character that although training of the gun at the maximum speed under the action of the training mechanism is permitted, as soon as this speed is exceeded as aforesaid the increase of pressure in the dash pot will cause the movement of the gun to be checked.

In order that the said invention may be clearly understood and readily carried into effect we will describe the same more fully with reference to the accompanying drawings, in which:—

Fig. 1 is a front elevation, with a portion thereof in section, showing a gun mounting provided with a constructional form of our improvements.

Fig. 2 is a side elevation of Fig. 1 with a portion thereof in section on the line 1, 1 of Fig. 1.

Fig. 3 is a sectional side elevation showing a portion of a gun mounting provided with another constructional form of our improvements, and

Fig. 4 is a section taken approximately on the line 2, 2 of Fig. 3.

A is the gun and A' is the carriage. In both the examples shown the aforesaid dash-pot comprises a piston B working in a cylinder B' filled with oil or other suitable liquid.

In Figs. 1 and 2 the cylinder B' is attached to the gun carriage and is arranged vertically beneath the gun and forward of the gun trunnions. Movement of the piston in the cylinder B' causes the liquid to be forced from one side to the other of the piston through a passage b' whose area is controlled by an adjustable plug b². In order to impart movement to the piston B in training the gun, the piston rod b is formed with quick pitch screw threads c engaging in a nut C driven by or forming part of a pinion C' gearing with a horizontal rack C² attached to the base of the pedestal. The piston B is prevented from rotating by a key b^x in the cylinder B'. A detachable cover c^x is provided for preventing grit and other foreign substances from gaining access to the screw threads c and the nut C; this cover has been removed in Fig. 1.

The flow of the liquid through the passage b' is so adjusted by the plug b² that if the piston B should attempt to move at a greater speed than that determined by the maximum training speed of the gun under the action of the training mechanism, this movement of the piston will be checked by the liquid being unable to flow fast enough through the said passage b' and the liability of the gun "taking charge" as aforesaid is avoided.

In Figs. 3 and 4 the piston rod b is connected by a vertical pivot b³ to a stationary bracket B³ which is preferably, as shown, attached to the under side of the shield roof B⁴. This bracket is stayed by rods b⁴, b⁴. The pivot b³ is so arranged that its axis is some distance from the axis of training, which is indicated at x in Fig. 4. Thus when the gun is being trained the piston B will be moved within the cylinder B'. The latter is horizontally arranged on the upper part of the carriage and is connected thereto by a vertical pivot b⁵. In this construction the passage of the liquid from one side to the other of the piston B is controlled by a valve key B^x which is constructed to give a similar result to that obtained by the plug b² as described with reference to Figs. 1 and 2.

In each of the constructions shown the cylinder B' is provided with a safety valve B⁵.

It is to be understood that the dash pot and its associated parts may if desired be arranged otherwise than described above.

What we claim and desire to secure by Letters Patent of the United States is:—

1. In a naval gun mounting, the combination of training mechanism for shifting the gun a predetermined maximum speed and a retarding mechanism for the gun, said retarding mechanism being designed to allow free movement of the gun at speeds less than said predetermined maximum speed but to prevent movement of the gun in excess of said predetermined maximum speed.
2. In a naval gun mounting, the combination with the gun and its carriage of training mechanism for shifting the gun carriage laterally at speeds not exceeding a predetermined maximum speed to train the gun in a horizontal plane, and a retarding mechanism for the gun carriage, said retarding mechanism being designed to allow free movement of the gun carriage at speeds less than said predetermined maximum speed but to prevent movement of the gun carriage in excess of said predetermined maximum speed.
3. In a naval gun mounting, the combination of training mechanism for shifting the gun a predetermined maximum speed and a retarding mechanism for the gun, said retard-

ing means comprising a part carried by the gun, a relatively fixed part and connections between the parts, allowing free relative movement thereof at speeds less than said predetermined maximum speed, but preventing relative movement of said parts at speeds in excess of said predetermined maximum speed.

4. In a naval gun mounting, the combination of training mechanism for shifting the gun a predetermined maximum speed, and a retarding mechanism for the gun, said retarding means comprising a piston, a cylinder, one of said parts being connected to the gun for movement therewith, the other of said parts being relatively fixed, a liquid in said cylinder to be circulated by the relative movement of the piston, and means for controlling the circulation of said fluid to prevent movement of said gun at speeds in excess of said predetermined maximum speed while permitting free movement of the gun at lower speeds.

In testimony whereof we affix our signatures:

ARTHUR TREVOR DAWSON.
GEORGE THOMAS BUCKHAM.
ERNEST FRANK ELLIS.
